INJECTION GUN

Fred G. Parisi, New Haven, Conn., assignor to E. R. Squibb & Sons, Inc., New York, N.Y., a corporation of Delaware

Filed June 28, 1966, Ser. No. 2,843

Term of patent 14 years

(Cl. D83—12)

FIG. 1 is a top plan view of an injection gun showing my design;

FIG. 2 is a side elevation thereof;

FIG. 3 is a rear elevation thereof; and

FIG. 4 is a bottom plan view thereof.

I claim:

The ornamental design for an injection gun, as shown.
